TIRE

John O. Antonson, Akron, Ohio, assignor to The B. F. Goodrich Company, New York, N. Y., a corporation of New York

Application March 25, 1955, Serial No. 35,195

Term of patent 14 years

(Cl. D90—20)

Fig. 1 is a perspective view of a tire showing my new design; and

Fig. 2 is a fragmentary section through the tire taken on line 2—2 of Fig. 1.

The full line portion of the drawing is repeated throughout the circumference of the tire disclosed by means of dotted lines.

I claim:

The ornamental design for a tire, as shown and described.
